UNITED STATES PATENT OFFICE

JAMES W. HAMMOND, OF WALPOLE, MASSACHUSETTS, ASSIGNOR TO BIRD MACHINE COMPANY, OF WALPOLE, MASSACHUSETTS, A CORPORATION OF MASSACHUSETTS.

SCREEN FOR PAPER PULP.

Application filed April 2, 1924. Serial No. 703,778.

To all whom it may concern:

Be it known that I, JAMES W. HAMMOND, a citizen of the United States, residing at Walpole, in the county of Norfolk and State of Massachusetts, have invented certain new and useful Improvements in Screens for Paper Pulp, of which the following is a specification.

This invention relates to screens of the ¹⁰ flow type for paper stock or pulp in which the stock is fed to a vat wherein the screen is partially submerged, the finer material passing inwardly through the screen to the interior thereof, from which it is discharged, ¹⁵ while the coarse material remains in the vat and from which it is removed. In screens of this type, it is the common practice to remove the coarser materials from the bottom of the vat in which the screen operates ²⁰ through a valve which is left open to a certain degree or extent during the entire run of the vat. As will be appreciated, considerable fine stuff will pass out along with the water and the coarser material through the ²⁵ open valve, thus allowing a lot of the stock and water to be discharged through the outlet pipe with a consequent loss of fine stuff. Where the valve is not left open it is necessary for the operator to open the same periodically for a short interval of time, and under this operation it is found that the dirt and coarse material is liable to fill the vat sufficiently to stop up the screen openings or ³⁰ slots so that the fine stuff cannot pass there-through and on its way to the paper machine. Moreover the attendant is liable to forget to open the valve with the consequence that the discharge may become plugged. ³⁵

The present invention has for its main object the provision of means for automatically taking care of the removal of the coarser material, and for its further object means whereby the coarser material will be automatically fed toward the valve discharge or the well or pocket to which the valve is attached.

The invention is illustrated in the annexed drawings, wherein,

Fig. 1 is a sectional elevation of an inflow screen adapted to handle stuff, the screen in the main being of the type set forth and claimed in United States Letters Patent to Clarke, No. 1,210,906, dated Janu-

ary 2nd, 1917, and to Bird, No. 1,304,258, ⁵⁵ dated May 20, 1919;

Fig. 2 an end elevation thereof;

Fig. 3 an enlarged vertical sectional view illustrating the valve employed to control the discharge of the coarse stuff and dirt; ⁶⁰

Fig. 4 a vertical sectional view showing the detail of the valve and its seat, the section being taken on the line 4—4 of Fig. 3, and

Fig. 5 a detail sectional view showing the ⁶⁵ operative connection between the valve actuating lever and the driving mechanism of the screens.

In the drawings, 1 represents the vat or chamber in which the screen is partially ⁷⁰ submerged, said vat being connected to the end frames 2 and 3 of the structure by flexible connections as 4 and 5, which allow the vat proper to be moved or vibrated sidewise with reference to the end frames 2 and 3. ⁷⁵ Mounted within the vat is a rotatable screen 6, one end, as 7, of which is closed while the opposite end is open, and discharges through an annular member or collar 8 into an off-take or box 9. Rotary motion is imparted ⁸⁰ to the screen through a band pulley 10 through pinion 11, gear 12, pinion 13, and the relatively large gear 14. Said latter gear is splined to a shaft 15 which is mounted in a suitable bearing formed in the fixed ⁸⁵ frame 3, the inner end of the shaft being rigidly affixed to the closed end 7 of the screen.

The vibratory movement is imparted to the vat through any suitable mechanism ⁹⁰ which in the present instance is shown as a shaft 16 carrying a cam 17, which latter imparts endwise movement to a rod or pitman 18 adjustably attached to downwardly extending arm 19 fulcrumed at 20 upon a fixed or rigid post or standard 21. The arm 19 is pivotally connected to the vat frame as at 22, and said frame at its opposite side is supported upon yielding or spring members 23, one of which is shown in Fig. 2. It will ¹⁰⁰ thus be seen that while the screen partakes of a rotary motion, the vat is vibrated and this causes the stuff within the vat to surge against the screen and permits the fine stuff to pass inwardly through the perforations ¹⁰⁵ in the screen.

The bottom of the vat is provided with a well or funnel-shaped member 24, adapted

to receive the coarse material which settles in the lower portion of the vat. To facilitate the entrance of such material into the well or opening, I preferably provide the 5 outer surface of the screen with a series of spirally arranged or inclined blades or flights. Said blades or flights, which are preferably provided with flexible wiping edges, are spaced at an angle to each other 10 and to the axis of the screen. The flights are arranged in pairs spaced about the outer surface of the screen, the members of the various pairs being preferably arranged at varying distances from each other, i. e., the 15 members of one pair are arranged adjacent the ends of the screen as at 25, while the next succeeding pair are closer together as at 26, and so on throughout the series until the final pair abut each other, as at 27. Said 20 last pair, as will be noted, stand in line with the discharge opening 24. These flights therefore gradually and constantly move the coarse stuff along the lower portion of the vat from the ends toward the discharge 25 opening, and the final pair of flights 27 bring it directly over the funnel-shaped opening or discharge member 24.

Secured to the lower end of the funnel shaped discharge member 24 is an extension 30 or mouthpiece 28 which has attached to it a valve casing 29 having a valve opening 30 adapted to co-operate with a valve 31 which is formed as an extension of an arm 32, said arm extending laterally and to one side of 35 the valve casing, as best shown in Figs. 1 and 3. Pivots connected to the outer free end of said arm is a link 33 adjustable as to length, said link in turn being connected to a lever 34 which is fulcrumed at 35, the opposite end of the lever in turn being connected to a rod 36, the upper end of which is attached to a radius bar 37 pivotally secured, as at 38, to the end frame 3 of the machine. The pin 39 (see Fig. 5), which secures the rod 36 to the radius bar 37, forms 45 the support for a roller or bowl 40, which latter stands in the path of a cam 41 (see Figs. 1 and 2), secured to the inner face of the gear 14 and extending outwardly into 50 the path of the roller. The weight of the lever 34, the link 33, and the arm 32 which is attached to the valve, is sufficient to hold the valve in its normally closed position, counteracting the weight of the short arm 55 of the lever 34 to the right of the fulcrum 35 and the weight of the rod 36 and the radius bar 37. For each revolution of the gear 14, the cam 41 will strike the roller 40 to depress the short arm of the lever 34 raising 60 the opposite end and throw the link 33, rocking the valve from its closed position to the open dotted line position shown in Fig. 3. The cam 41 is positioned on the gear 14 so that the valve will be opened at approximately the time the flights or scrapers 27

come into alignment with the discharge opening 24, so that the coarse material and dirt which is finally gathered up by such pair of flights will be over the opening 24 just at, or slightly prior to, the opening of 70 the valve 31. Thus the coarse material is automatically and periodically discharged from the lower portion of the vat, and the uncertainty of the human element is eliminated from the operation of the machine 75 where the workman is depended upon to open the valve from time to time. Again, no waste of fine stuff, other than a very small amount, takes place. Again, the construction has the advantage of affording a 80 wide open valve with minor waste as distinguished from a small opening and a continued waste where the valve is mechanically set to produce a constant discharge. 85

It is of course conceivable in the broader aspect of the invention that the flights may be omitted and the valve operated mechanically, but the presence of the flights, which act to gather the coarse material and bring it to the point of discharge, materially enhance the successful operation of the screen. Wash pipes for the interior and exterior of the screen are disclosed, but, as they form 90 no part of the invention, specific reference thereto is omitted. 95

No claim is made herein specifically to the flight or scraper arrangement, other than in combination with the automatically operating valve, as such flight arrangement, as such, is not of my invention. 100

What I claim is:

1. In a screen for paper stock, the combination of a vat having a discharge opening in the lower portion thereof for coarse material and dirt, a screen mounted in the vat, a valve controlling the discharge opening, means for rotating the screen, and mechanically actuated means for periodically opening the valve. 105

2. In a screen for paper stock, the combination of a vat having a discharge opening in the lower portion thereof for coarse material and dirt, a screen mounted in the vat, a valve controlling the discharge opening, means for rotating the screen, and means working in timed relation with the screen for periodically opening the valve. 110

3. In a screen for paper stock, the combination of a vat having a discharge opening in the lower portion thereof for coarse material and dirt, a screen mounted in the vat, means for rotating the screen, a valve controlling the discharge opening, and means associated with the screen-operating means for periodically opening the discharge valve. 115

4. In a screen for paper stock, the combination of a vat having a discharge opening in the lower portion thereof for coarse material and dirt, a screen mounted in the vat, means for rotating the screen, means 120

for oscillating the vat to produce a surging action therein with reference to the screen, a valve for controlling the discharge opening, and mechanical means for periodically opening the discharge valve.

5. In a screen for paper stock, the combination of a vat having a discharge opening in the lower portion thereof for coarse material and dirt; a screen mounted in the 10 vat; means for rotating the screen; a series of vanes arranged obliquely with reference to the axis of the screen about the outer surface thereof, said vanes serving by reason of their inclination to move the coarse 15 material and dirt along the lower portion of the vat toward the discharge opening; a valve controlling said opening; and mechanically actuated means for periodically operating the valve.
20. 6. In a screen for paper stock, the combination of a vat having discharge opening in the lower portion thereof for coarse material and dirt, a cylindrical screen mounted in the vat, means for rotating the screen, a series of flights spaced at an angle to each 25 other and to the axis of the screen, said

flights being secured to and spaced about the outer face of the screen in pairs, the members of the various pairs in the series, beginning at a given point upon the screen, 30 gradually approaching each other, a valve for controlling the discharge opening, and means for operating said valve in timed relation to the rotation of the screen, the parts being so arranged that the valve is opened 35 when the pair of flights which are closest together come into juxtaposition with the discharge opening.

7. In a screen for paper stock, the combination of a vat having a discharge opening in the lower portion thereof for coarse material and dirt, a screen mounted in the vat, means for rotating the screen, a pivoted valve controlling the discharge opening, a cam associated with the screen operating 40 means, and means extending from the valve and standing in line with the path of movement of the cam, said cam co-operating with said means to open the valve.

In testimony whereof I have signed my 50 name to this specification.

JAMES W. HAMMOND.
